CORPORATION STOP AND TOOL

Walter J. Bowan, Decatur, Ill., assignor to Mueller
Co., Decatur, Ill., a corporation of Illinois

Application October 15, 1938, Serial No. 235,247

4 Claims. (Cl. 81—53)

This invention relates to a corporation stop and to a tool for turning corporation stops to or from position. While the particular tool and stop to be hereinafter described cooperate most effectively, they may be used independently, that is to say, the stop may be inserted or removed by other tools and the tool may be used for the insertion or removal of other designs of stops.

The usual corporation stop comprises a body and threaded nipples projecting from opposite ends of the body, the body constituting a valve housing. One of the nipples is designed to be threaded in an aperture in a main and the other, which is the outlet nipple, is designed to receive a coupling. In the usual inserting operation, for example, a tool is threaded on the outlet nipple until it jams, thus enabling rotation of the tool to be imparted to the stop. Due to this jamming the stop sometimes follows the tool when it is sought to remove the latter by reverse rotation, and frequently, moreover, the nipple is injured. It is an object of the present invention to avoid this jamming by transmitting rotation of the tool directly to the stop body, the nipple itself taking no part in torque transmission and serving merely to hold the stop and tool together during insertion.

In the accompanying drawing I have shown, by way of example, two forms which the new tool may take and also a new form of stop body particularly adapted for cooperation with the new tool and tools of similar type. I shall describe the invention with reference to this drawing in which

Figure 1 shows an elevation of one form of the new tool applied to the improved stop, a portion of a main being shown in cross section.

Figure 2 is a section substantially on line 2—2 of Figure 1.

Figure 3 is a section substantially on line 3—3 of Figure 2.

Figure 4 is an axial section of the second form of tool.

Figure 5 is an elevation of the tool of Figure 4 partly in section and partly broken away, and

Figure 6 is an elevation of the tool of Figures 4 and 5 as seen from the left of these figures.

Referring to the drawing, and first to Figures 1, 2 and 3, reference numeral 10 designates generally the stop and reference numeral 11 the tool. The stop 10 comprises a body 10' housing a plug 12 which controls flow through the stop. Nipples 13 and 14 project from opposite ends of the body 10', the first being designed for threading in an aperture 15 of a main 16 and the sec-

ond being primarily designed for the reception of a coupling. At the base of the nipple 14 the body is somewhat laterally expanded transversely of the plug axis to provide shoulders as at 17 lying in a common plane and these shoulders are provided with diametrically opposed recesses 18 and 19 which are open toward the nipple 14 and each of which has parallel axially extending lateral walls, as at 21 and 22, Figure 1. The shoulders surmount flat parallel lateral faces of the stop body.

The tool 11 comprises a shank 23 designed for reception in the socket of the usual boring bar. At one end of the shank is a head 24, which, as here shown, is cylindrical and is integral with the shank and eccentrically disposed relative to the axis of the latter. The axis of the head 24 is parallel to the axis of the shank.

In the head 24 is formed a threaded socket 25 which is coaxial with the shank 23. Due to the eccentricity of the head relative to the shank and the coaxial disposition of the socket relative to the shank, the outer face of the head is in the form of a rim 26 of varying radial width. At or about the widest part of the ring 26 it is provided with a bore 27 parallel to the tool axis, the bore being closed toward the shank by an end wall 28. A slot 29' extends part way along bore 27 and has closed ends.

Slidably in bore 27 is the shank portion 29 of a plunger 30 which has a foot or abutment portion 31 projecting beyond the head in the opposite direction from the shank. The foot 31 has, as here shown, an inward extension 32 and a flat forward surface 33. The trailing portion of the foot 31 is beveled to provide a cam surface 34. Shank 29 is provided with a through transverse bore which is threaded and receives a screw 35' whose head portion projects through slot 29'. Desirably the plunger 30 is yieldingly projected by a compression spring 36' disposed between the end of the shank and wall 28.

When the stop is to be inserted, the tool 11 is threaded on nipple 14 while plunger 31 is manually retracted against the action of spring 36', this being conveniently accomplished by engaging the projecting end of the screw 35' with the thumb as the tool is held in the hand. The relation of parts is such that prior to the full reception of the nipple in the socket the plunger may be released to enable the abutment portion 31 to be projected into one of the recesses, as 19. Figures 1 and 2, a substantial distance. When turning force is now applied to the tool it is positively imparted to the stop by reason of the abut-

ment of face 33 of the plunger with wall 21 of the recess. When the stop has been completely turned home, the tool is reversely rotated, the cam surface 34 of the plunger riding over the edge of the recess walls as at 22 so that the tool is readily removable.

If the tool is to be used for the removal of a stop it is only necessary to reverse the position of the plunger in bore 27. This is done by removing screw 35', turning the plunger through 180° and replacing the screw. With this arrangement the tool may be threaded on nipple 14, the cam face 34 eventually riding over the top edges of the recess walls as at 21. When the nipple has been sufficiently received in the socket the tool is reversely rotated causing the flat face 33 of the plunger to abut one of the recess walls 22, whereupon the stop is forced to follow the tool.

While the stop might be provided with only one recess, two are preferred, since it gives a more balanced appearance and since in some cases it may be desired to apply torque at both sides of the stop.

The modified form of tool shown in forms 4 to 6 comprises a shank 35 and a coaxial cylindrical head 36 provided with a coaxial threaded socket 37. At one edge the head 36 is provided with a non-round (for example, rectangular) axially extending groove 38 which is open at its end opposite the shank and closed by a wall 39 at its other end. A plunger 40 has a shank received in and mating with the groove or guideway 38 so as to be non-rotatable thereto, the plunger having a projecting foot or abutment portion 41 generally similar to that of the form first described and entirely similar in function. A ring 42 embraces the head 36 and is secured thereto by screws 43. The ring is provided with an internal annular groove 44 in which is received a pin 45 which is fixed in the shank of plunger 40. Ring 42 serves to hold the plunger in the groove 38 and the groove 44 in conjunction with pin 45 limits the reciprocating range of the plunger. The plunger is preferably yieldingly projected by a spring 46 disposed between the end of the plunger shank and wall 39.

The tool just described is used in exactly the same manner as the tool of Figures 1 to 3. If desired, two plungers may be provided at diametrically opposite points for simultaneous coaction with diametrically opposite side walls of the stop recess.

It will be understood that the invention is not limited to the details of form and arrangement shown and described and that variations in these matters may be made without departure from the following claims.

I claim:

1. A tool for use in turning corporation stops, said stops including a body and threaded nipples projecting from opposite ends of said body, said body including a side portion adjacent one of said nipples faced oppositely to the threading direction of the latter, said tool comprising a shank portion and a head portion at one end of the shank portion having a threaded socket therein coaxial with said shank portion and engageable with said one of said nipples, and a retractile abutment projectable in the axial direction of the tool beyond the head portion in the opposite direction from said shank portion, said abutment being constituted by a plunger reciprocable in an

axially extending guideway in said head portion radially outwardly of said socket; said abutment being maintainable in retracted relation so that its leading edge will clear said side portion as the 5 socket is threaded on said one of said nipples and being then projectable so that its leading edge will firmly engage said side portion as threading of the socket on said one of said nipples continues and prior to such full reception of said one of said nipples in said socket as would cause jamming, whereby to positively transmit rotation of the tool to the stop in the inserting direction of the latter; said abutment due to its retractability riding over any body portion encountered by it upon reverse rotation of the tool relative to the stop so that the tool is readily removable from the stop.

2. A tool for use in turning a corporation stop, said stop comprising a body and threaded nipples projecting from opposite ends of said body, said tool comprising a shank portion and a head portion at one end of said shank portion having a threaded socket therein coaxial with said shank portion and engageable with one of said nipples, 10 an axially extending guideway in said head portion radially outwardly of the socket, and a plunger reciprocable in said guideway between limit positions and when in one limit position projecting beyond the head portion in the opposite direction from said shank portion, said plunger in retracted position permitting the threading of said one of said nipples in said socket and then, in projected position, engaging a portion of the stop body to transmit rotation of the 15 tool in one direction to the stop with said one of said nipples less than fully engaged in said socket, the outer end of said plunger having a cam surface adapted to ride over the cam body upon reverse rotation of the tool relative to the stop, and the plunger being reversible so that it may be rendered effective either for stop insertion or removal.

3. A tool according to claim 1 wherein the plunger has a round shank portion in said guideway, wherein a slot having closed ends extends longitudinally of said guideway, and wherein a screw is threaded into said round shank portion and extends into said slot whereby to prevent rotation of said plunger and to limit the reciprocation thereof.

4. A tool for use in turning a corporation stop, said stop comprising a body and threaded nipples projecting from opposite ends of said body, said tool comprising a shank portion and a head portion at one end of said shank portion having a threaded socket therein coaxial with said shank portion and engageable with one of said nipples, 20 an abutment carried by said head portion movable between a retracted position and a projected position in which latter it projects substantially beyond said head portion in the opposite direction from said shank portion, said abutment in retracted position permitting the threading of said one of said nipples in said socket and then, in projected position, engaging a portion of the stop body to transmit rotation of the tool to the stop with said one of said nipples less than fully engaged in said socket, and a projection on said abutment remote from its outer extremity manually engageable for moving said abutment.

WALTER J. BOWAN.
